UNITED STATES PATENT OFFICE.

EARL R. JOHNSON, OF CHICAGO, ILLINOIS.

FRAME AND MOUNTING.

Application filed October 27, 1926. Serial No. 144,443.

The present invention pertains in general to frames and more particularly to desk plates and the like.

It is the practice in many business offices 5 to mount desk plates on the desk of an employee to indicate the employee's name and duties. These plates, however, are not used very extensively for the simple reason that those available on the market are exceedingly 10 expensive. In fact, most of these plates are formed of expensive castings and require considerable machining in order to give them a high degree finish. Obviously, it is the casting and machining operations which 15 augment the cost of the desk plate.

I propose to provide a highly simple and inexpensive desk plate including means for preventing the accidental displacement of the card inserted in the device. The device 20 proper includes a frame and an integral mounting both of which are punched from a single sheet of metal so as to enable the device to be economically manufactured.

In accordance with the general features 25 of my invention, I provide a device comprising a frame including a peripheral slot adapted to receive an insert, the slot being defined by flaps turned back over the frame, and a supporting member connected to the 30 frame and disposed at an angle thereto. The flaps defining the peripheral slot are preferably located between the frame and the supporting member so as to cause the frame to present a substantially flat and smooth 35 appearance. Also, the flap associated with one end of the frame is preferably spaced from the associated side flaps so as to permit of the ready insertion of a card in the said frame. Moreover, the said end flap is 40 adapted to prevent the insert from falling from the frame when the frame is turned upon end.

The main supporting member of my device comprises a plate formed integral with 45 the frame and preferably connected at its end to the ends of the frame. This plate is disposed at a suitable angle with respect to the plane of the frame and co-operates with the frame to support the device. Furthermore, 50 in order to reinforce the construction I provide the end flaps with extensions which lie over the inner surface of the supporting plate or member. These extensions are also formed integral with the ends of the 55 supporting plate and although they are formed integral with the end flaps of the

frame, they are disposed at an angle to these flaps. These extensions not only reinforce the ends of my desk plate but also tend to prevent the ends of the supporting plate 60 from being distorted.

Other objects and advantages of my invention will more fully appear from the following detailed description taken in connection with the accompanying drawing 65 which illustrates several embodiments thereof and in which,

Figure 1 is a perspective view of a desk plate embodying the features of my invention;

Fig. 2 is a sectional view taken on substantially the line 2—2 of Fig. 1 looking in the direction indicated by the arrows and illustrating the flaps defining the peripheral slot in the frame;

Fig. 3 is a sectional view taken on the line 3—3 of Fig. 1;

Fig. 4 is a sectional view taken on the line 4—4 of Fig. 1;

Fig. 5 is a view of a modification of my 80 invention illustrating means for mounting the frame of my invention upon a wall or the like; and

Fig. 6 is a sectional view taken on the line 6—6 of Fig. 5 looking in the direction indicated by the arrows.

Referring now to the drawing in detail in which like reference numerals designate similar parts throughout the several views, 90 10 denotes generally a frame embodying the features of my invention. Connected to the upper edge of this frame and disposed at an angle to the plane of the frame is a supporting plate or member 11. I preferably dispose the frame 10 at an angle of approximately 60° with respect to the member 11. This frame 10 when taken in connection with the plate 11 forms a desk plate particularly adapted for use in business offices.

The frame 10 proper includes a main 100 frame portion 12 which is preferably rectangular in shape and defines a rectangular opening 13. Formed integral with the sides of this main frame portion 12 are a pair of side flaps 14 and 15 (Fig. 2). The flap 15 is preferably made a trifle longer than the flap 14 and extends clear to the ends of the frame portion 12. A portion of the flap 15 is cut away at 16 in order to form an opening, the purpose of which will be described hereinafter. Similarly, a portion of the flap 14 is cut away at 17 in order to form an 105 110

opening for cooperating with the opening at 16. These two openings permit of the ready insertion of a card 18 into the spaces separating the flaps from the main portion 12. 5 It will be noted at this time that in Fig. 1 I have illustrated the outer side of the frame 10 and that in Fig. 2 I have illustrated the inner side of the frame 10.

Formed integral with each end of the 10 main frame portion 12 is an end flap adapted to co-operate with the side flaps in properly enclosing the card 18. I have designated the two end flaps by reference characters 19 and 20. The side flaps and the end flaps 15 when taken together in reality define a peripheral slot adapted to enclose the peripheral edge of a card such as the card 18. Moreover, the flap 20, which is associated with the two previously mentioned openings, 20 serves to prevent the card in the frame from being displaced therefrom when the frame is turned upon end.

The plate 11 is connected to the frame portion 12 at its end by means of a pair of 25 spaced extensions 21 and 22 formed integral with the main frame portion. The two extensions 21 and 22 are separated by a rectangular opening 23' from which the flap 14 has been taken. Also, the end flaps 19 and 20 of the frame have formed integral therewith 30 a pair of extensions 23 and 24 which are also formed integral with the ends of the plate 11. These extensions 23 and 24 serve to reinforce the ends of the plate 11. They also 35 co-operate with the extensions 21 and 22 to reinforce the hinge connection between the frame and the member 11. The end flaps and the associated extensions 23 and 24 are in reality continuous strips of material. In 40 fact, my entire device is formed from a single piece of substantially flat metallic material.

The device of my invention illustrated in 45 Fig. 1 can be very economically manufactured from a single sheet of metallic material. Obviously, the first step in the manufacture of the device will be the slitting of the sheet to define the flap of the frame as well as the extensions 23 and 24. After the 50 slitting operation the side flaps are bent into their proper position and the portions 16 and 17 are removed to define the previously mentioned openings. Thereafter, the end flaps and the integral extensions 23 and 24 are 55 bent over on top of the main portion of the sheet. Of course it will be evident that it will be necessary to remove a rectangular piece of material from the sheet in order to define the opening 13.

60 When all the flaps have been bent into their respective positions, the sheet is bent into the two parts, namely, the frame 10 and the supporting plate 11. I preferably bend these two parts into an angular construction 65 with the flaps disposed in the space defined

by the said two parts. In other words, all of the flaps of the frame as well as the extensions 23 and 24 will be located between the frame portion 12 and the supporting member 11, thus causing the frame to present 70 a relatively smooth and flat appearance.

The card 18 can, with facility, be inserted in the peripheral slot defined by the side and end flaps through the means of the openings 75 at 16 and 17. Moreover, when said card is in position in the frame it cannot be accidentally displaced should the frame be turned up on its end.

In Figs. 5 and 6 I have illustrated a modification of my invention. In this form of 80 my invention the frame is of substantially the same construction as the frame 10 in the preferred form. This modification is not as well adapted for desk use as the form shown in Fig. 1 but is designed for attachment to a 85 wall or the like. In other words, this form does not have a mounting plate such as the plate 11 but is equipped with ears for fastening the frame to the wall as will now be described in detail.

90 The frame comprises a main frame portion 30 which is rectangular in shape and defines a rectangular opening 31. Formed integral with the portion 30 are a pair of side flaps 33 and 34 which co-operate with end flaps 35 and 36 in defining a peripheral slot between the main frame portion and the flaps. This peripheral slot is adapted to receive an insert such as a card.

In order to permit of the ready insertion 100 of the card in the frame I preferably space the ends of the side flaps 33 and 34 from the end flap 35 as indicated at 37 and 38. The openings at 37 and 38 permit the card to be inserted with facility into the previously 105 mentioned peripheral slot.

The mounting means for this frame comprises a pair of laterally extending ears 39 and 40 cut from the side flap 33. These two ears are formed integral with the main 110 portion 30 and each of them has an aperture 41. Obviously, the frame can be attached with facility to a wall or the like through the means of the two mounting 115 ears 39 and 40.

120 Now I desire it understood that although I have described several embodiments of my invention, the invention is not to be thus limited but only in so far as defined by the scope and spirit of the appended claims.

I claim:

1. As an article of manufacture, a frame including a peripheral slot adapted to receive an insert, said slot being defined by 125 flaps turned back over the frame, a supporting member connected to the frame and disposed at an angle to the frame with the ends opposite the ends of the frame, said flaps being located between the frame and 130

the member, and a reinforcing element for each end of the supporting member connected to the associated end flap of the frame within the angular space defined by said frame and member.

2. As an article of manufacture, a frame including a peripheral slot adapted to receive an insert, said slot being defined by flaps turned back over the frame, a supporting member connected to the frame and disposed at an angle to the frame with its ends opposite the ends of the frame, said flaps being located between the frame and the member, and an extension formed integral with each end flap of the frame and with the associated end of the supporting member for reinforcing said member, said extension being located in the angular space defined by said member and said frame.
3. As a new article of manufacture, a holding device formed of a single sheet of material bent to form a front plate and a back plate disposed in angular relation, said front plate having a display opening and the back plate being slit from its upper edge and to within a short distance of each end forming a flap integrally connected to the upper edge of the front plate, said flap being turned forwardly into spaced parallel relation to the upper portion of the front plate and defining therewith a channel element, the front edge portion of the sheet being turned inwardly into spaced
- 5 10 15 20 25 30

parallel relation to the lower portion of the front plate and forming therewith a channel element, the end portions of the sheet being bent inwardly forming channel elements reinforcing the connection between the front and back plate at the ends thereof, said inwardly bent portions being spaced away from the end portions of the front plate and forming therewith end channel elements.

4. As a new article of manufacture, a holding device formed of a single sheet of material bent to form a front plate and a back plate disposed in angular relation, said front plate having a display opening and the back plate being slit from its upper edge and to within a short distance of each end forming a flap integrally connected to the upper edge of the front plate, said flap being turned forwardly into spaced parallel relation to the upper portion of the front plate and defining therewith a channel element, the front edge portion of the sheet being turned inwardly into spaced parallel relation to the lower portion of the front plate and forming therewith a channel element, the end portions of the front plate being bent inwardly and spaced away from the inner face of the front plate and forming therewith end channel elements.

In witness whereof, I hereunto subscribe my name this 23rd day of October, 1926.

EARL R. JOHNSON.
